Primary Examiner — Deanna L Pratt(74) *Attorney, Agent, or Firm* — Saidman DesignLaw Group, LLC(57) **CLAIM**

The ornamental design for furniture for aircraft, as shown and described.

DESCRIPTION

FIG. 1 is a perspective view of a first embodiment of furniture for aircraft showing our new design;
 FIG. 2 shows a first alternate position thereof;
 FIG. 3 is a top view of FIGS. 1 and 2;
 FIG. 4 shows a second alternate position thereof;
 FIG. 5 shows a third alternate position thereof; and,
 FIG. 6 is a top view of FIGS. 4 and 5.
 The drawings include CAD lines that represent contour and not surface decoration.
